DESIGN FOR A HOLDER FOR CANDLES OR OTHER ARTICLES

Russell S. Walker, Duluth, Minn.

Application March 21, 1938, Serial No. 76,001

Term of patent 7 years

To all whom it may concern:

Be it known that I, Russell S. Walker, a citizen of the United States, residing at Duluth, in the county of St. Louis and State of Minnesota, have invented a new, original, and ornamental Design for a Holder for Candles or Other Articles, of which the following is a specification, reference being had to the accompanying drawing, forming part thereof.

I claim:

The ornamental design for a holder for candles or other articles, as shown.

RUSSELL S. WALKER.
